CLAIM

I claim the ornamental design for the bowl, as shown and described.

DESCRIPTION

FIG. 1 is a perspective view of a bowl showing my new design;

FIG. 2 is a front elevational view thereof, the rear elevational view, and side elevational views, being the same as the front elevational view;

FIG. 3 is a bottom view thereof;

FIG. 4 is a top view thereof;

FIG. 5 is a perspective view of a second embodiment of the bowl showing my new design;

FIG. 6 is a front elevational view of the second embodiment, the rear and side elevational views being the same as the front elevational view;

FIG. 7 is a bottom view of the second embodiment; and,

FIG. 8 is a top view of the second embodiment.
